UNITED STATES PATENT OFFICE.

HAYDN OSWALD WILLIAMS, OF SPERLING, AND WILLIAM JOSEPH MILLER, OF VANCOUVER, BRITISH COLUMBIA, CANADA.

LOGGING-CAR.

1,387,822.

Specification of Letters Patent. Patented Aug. 16, 1921.

Application filed August 13, 1920. Serial No. 403,292.

To all whom it may concern:

Be it known that we, HAYDN OSWALD WILLIAMS and WILLIAM JOSEPH MILLER, both subjects of the King of Great Britain, and 5 residents, respectively, of Sperling and Vancouver, both in the Province of British Columbia, Canada, have invented certain new and useful Improvements in Logging-Cars, of which the following is a specification.

Our invention relates to improvements in logging cars and the object of our invention is to devise an improved form of log support bunk which is comparatively simple 15 in construction and easy of operation capable of being readily adapted to the ordinary logging cars in use at the present time. A further object is to devise a releasable means which will efficiently hold the logs in place 20 and which may be released from the opposite side of the car, thus preventing danger to workmen from logs rolling from the car.

We attain these objects by the construction illustrated in the accompanying drawings in which—

Figure 1 is a perspective view of a logging car with which our invention is embodied.

Fig. 2 is a side view of the log bunk, partly in section.

Fig. 3 is an end view of the bunk, partly in section.

Fig. 4 is a detail view of the chain fastening means.

Fig. 5 is a perspective view of the movable chock member.

Fig. 6 is a bottom plan view of the elbow extension.

Similar figures of reference indicate similar parts throughout the several views.

1 indicates a flat car of any approved make to the floor of which adjacent its opposite ends are secured transversely bunks 45 of timber 2 and 3, to the upper face of each of which and at one end are secured fixed chocks 4 and 5 the outer ends of which are upturned, as at 6, so as to form a stop, to prevent the outer row of the lower tier of 50 logs from falling outwardly. Secured to the opposite end of each bunk 2 and 3 are parallel guides 7 and 8, as shown in Fig. 3, between which are slidably mounted laterally adjustable chocks 9 and 10 respectively 55 of similar construction to the stationary

chocks 4 and 5, the movable chocks, however, being each provided on their lower faces with a plurality of spaced ribs or teeth 11. 12 and 13 indicate shafts extending longitudinally through the respective bunks 2 and 3 each of which shafts is provided with teeth 14 adapted to engage the teeth 11 of their respective chocks 9 and 10 to lock these in any position to which they may be moved, as is more fully hereinafter 60 described, and in order to enable quick and free engagement or disengagement of the shaft teeth and the chock teeth the latter are arranged slightly inclined on the lower face of the chocks, as indicated in Fig. 5. 70

15 and 16 indicate operating handles secured to the end of shafts 12 and 13 at the ends remote from the movable chocks 9 and 10. 17 and 18 indicate spring pressed latch members mounted adjacent the handles 75 adapted to be pressed in by them as they are moved around to operate the shafts, the latch members then springing out when the handles have been passed to prevent inadvertent return movement of the handles. 80 The opposite end of each shaft is provided with an elbow, indicated by the numeral 19 in Fig. 2, having a downwardly inclined outer face 20, a downwardly turned reduced extension 21 being provided on the 85 inclined face 20 so that the elbow and the extension form in effect a hook on which the end link of the chain may be engaged. The lower end of the extension is provided with a recess 23 in which normally rests 90 the hooked end 24 of an outwardly spring-pressed shaft 25 the engagement of the end 24 of which with the recess 23 prevents inadvertent rotation of the shaft, and the side walls of the recess are made inclined so that 95 the inclined surface of the wall riding on the end 24 as the shaft is turned presses inwardly the shaft 25 and allows the toothed shaft to be operated the amount required.

From the foregoing, it will be evident that 100 the extension 21 of the elbow 15 and the hook end 24 of the shaft 25 form in effect a shackle for engagement with one of the chains referred to hereafter.

26 and 27 indicate the chains for binding 105 the logs, each of which chains has a link, indicated by the numeral 22 in Fig. 2, adapted to engage freely the hooked end of its respective shaft 12 and 13 while the opposite end of each chain is secured respectively to 110

links 28 and 29 secured to the car, these links being wide at their lower ends as at 30 to permit the chains to be passed freely through while their upper ends are reduced, 5 as at 31, to a width just sufficient to receive a chain link edgewise so that the contiguous link being then on its flat, the chain is securely held from inadvertent displacement.

The manner in which the invention is operated and its utility will be apparent and may be briefly described as follows:—The logs, indicated by the numeral 32, are arranged in tiers on the car, the lower tier resting on the guides 7 and 8 and covering 15 plates 33 and 34 under which the respective chocks 9 and 10 slide. These chocks are then adjusted laterally to the width of the tier of logs so as to hold the logs close to one another and the shafts 12 and 13 are then operated to carry their teeth 14 into engagement with the respective chock teeth 11, thus preventing inadvertent displacement of the teeth so that the chocks are then locked in their adjusted positions. The respective shaft elbows 19 and extensions 21 20 now facing downwardly, as shown in Fig. 2, the links 22 of the chains are passed over the extensions 21, carried over the body of logs, and their free ends doubled and passed 25 through the wide ends of the links 28 and 29, the chains then being pulled tight after which the link of each chain which extends through the respective links 28 and 29 is turned edgewise and placed in the reduced 30 end of the links, being held against disengagement therefrom by the next chain link 35 which is turned transversely and thus the logs are securely bound to the car for transportation.

40 On reaching the delivery point to enable discharge of the logs from the car to be effected the shafts 12 and 13 are operated to carry the shaft teeth 14 clear of the chock teeth 11, this operation at the same time 45 turning the extensions 21 and elbows 19 upwardly so that the chain links 22 free themselves from the extensions, being assisted by the inclined elbow faces 20, the chocks 9 and 10 being forced outwardly by the pressure 50 of the logs so that the discharge of the logs is readily and easily accomplished without danger to the operator.

What we claim as our invention is:—

55 1. In a logging car, a laterally movable log chock, toothed on its underside, and a toothed shaft capable of actuation from the opposite side of the car the teeth of which are adapted to be carried into engagement with the chock teeth to maintain the chock in any laterally adjusted position, said shaft having its end on the movable chock side of the car curved to form a hook adapted to receive a chain link when the shaft is in the chock-teeth engaging position.

60 2. In a logging car, a laterally movable

log chock, toothed on its underside, a toothed shaft capable of actuation from the opposite side of the car the teeth of which are adapted to be carried into engagement with the chock teeth to maintain the chock in any laterally adjusted position, said shaft having its end on the movable chock side of the car curved to form a hook adapted to receive a chain link when the shaft is in the chock-teeth engaging position, said hook having a recess in its point, and a spring-pressed shaft having a curved end the point of which is adapted to seat in said recess whereby the said hook and said curved end then form a shackle. 70

75 3. In a logging car, a laterally movable log chock toothed on its underside, a toothed shaft capable of actuation from the opposite side of the car the teeth of which are adapted to be carried into engagement with the chock teeth to maintain the chock in any laterally adjusted position, said shaft having its end on the movable chock side of the car curved to form a hook adapted to receive a chain link when the shaft is in the chock-teeth engaging position, said hook having a recess in its inner side the walls of which incline outwardly, and a shaft having a curved end the point of which is adapted to seat in said recess whereby the said hook and said curved end then form a shackle, said shaft being longitudinally movable whereby it may be freed from the recess due to the bearing thereon of the recess-inclined wall 90 as the toothed shaft is actuated. 95

100 4. In a logging car, a laterally movable log chock toothed on its underside, a toothed shaft capable of actuation from the opposite side of the car the teeth of which are adapted to be carried into engagement with the chock teeth to maintain the chock in any laterally adjusted position, said shaft having its end on the movable chock side of the car curved to form a hook adapted to receive a chain link when the shaft is in the chock-teeth engaging position, said hook having a recess in its inner side the walls of which incline outwardly, a shaft having a curved end, the point of which is adapted to seat in said recess whereby the said hook and said curved end then form a shackle, said shaft being longitudinally movable whereby it may be freed from the recess due to the bearing thereon of the recess-inclined wall 110 as the toothed shaft is actuated, 115 an operating handle on the opposite end of the toothed shaft, and a trip latch for maintaining the shaft in position after operation. 120

125 5. In a logging car, a laterally movable log chock toothed on its underside, a toothed shaft capable of actuation from the opposite side of the car the teeth of which are adapted to be carried into engagement with the chock teeth to maintain the chock in any laterally adjusted position, said shaft having its end 130

on the movable chock side of the car curved to form a hook adapted to receive the end link of a chain passed across the car when the shaft is in the chock-teeth engaging position, and a link secured to the opposite side of the car and the chain through which a bight of the chain may be freely passed, said link being restricted at its upper end to permit insertion only of a chain link 10 edgewise.

6. In a logging car, a laterally movable log chock toothed on its underside, a toothed shaft capable of actuation from the opposite side of the car the teeth of which are 15 adapted to be carried into engagement with the chock teeth to maintain the chock in any laterally adjusted position, and an elbow-like extension on the end of said shaft provided with a reduced curved extension 20 whereby a hooked end is formed on said shaft adapted to receive a chain link.

7. In a logging car, a laterally movable log chock toothed on its underside, a toothed shaft capable of actuation from the opposite 25 side of the car the teeth of which are adapted to be carried into engagement with the chock teeth to maintain the chock in any laterally adjusted position, and an elbow-like extension on the end of said shaft provided 30 with a reduced curved extension whereby a hooked end is formed on the shaft adapted to

receive a chain link, the outer end of said elbow being formed with a downwardly and outwardly inclined face against which said chain link rests while in operative position. 35

8. In a logging car, a laterally movable log chock provided with teeth, and a rotary locking member provided with teeth adapted to mesh with the teeth of said chock to hold the latter in adjusted position. 40

9. In a logging car, a laterally movable log chock provided with teeth, a rotary shaft provided with teeth adapted to mesh with the teeth of said chock to hold the latter stationary, a handle carried by one end of said 45 shaft, and chain engaging means carried by the opposite end thereof.

10. In a logging car, a stationary chock, a second chock movable relatively to said stationary chock, means for releasably holding 50 said movable chock stationary including a shaft, a log engaging chain anchored at one end to the car, and coöperating means carried by the car and said shaft for securing the other end of the chain when the latter 55 has been passed around the logs supported between the two chocks.

Signed at Vancouver, B. C., Canada, this 2nd day of August, 1920.
